US00D801589S

(12) **United States Design Patent** (10) **Patent No.:** **US D801,589 S**
(45) **Date of Patent:** **** Oct. 31, 2017**

(54) **PROTECTIVE MASK**

(71) Applicant: **GI SPORTZ DIRECT LLC**, Sewell, NJ (US)

(72) Inventors: **Simon Benjamin Stevens**, Barnsboro, NJ (US); **Bryan Stowe**, Sewell, NJ (US)

(73) Assignee: **GI SPORTZ DIRECT LLC**, Sewell, NJ (US)

(**) Term: **14 Years**

(21) Appl. No.: **29/488,569**

(22) Filed: **Apr. 21, 2014**

Related U.S. Application Data

(60) Continuation-in-part of application No. 29/370,432, filed on Jun. 14, 2010, now Pat. No. Des. 703,388, which is a continuation of application No. 29/327,424, filed on Nov. 5, 2008, now abandoned, which is a division of application No. 29/253,707, filed on Feb. 10, 2006, now Pat. No. Des. 589,211.

(57)

CLAIM

The ornamental design for the protective mask, as shown and described.

DESCRIPTION

FIG. 1 is a front perspective view of a protective mask showing our new design;

FIG. 2 is a front elevational view thereof;

FIG. 3 is a right side elevational view thereof, the left side being a mirror image;

FIG. 4 is a top plan view thereof; and,

FIG. 5 is a bottom plan view thereof.

The details shown in broken lines form no part of the claimed design.

1 Claim, 4 Drawing Sheets
